UNITED STATES PATENT OFFICE.

OLE TILTON, OF PITTSBURG, PENNSYLVANIA.

WASHING-MACHINE.

SPECIFICATION forming part of Letters Patent No. 235,395, dated December 14, 1880.

Application filed August 21, 1880. (No model.)

To all whom it may concern:

Be it known that I, OLE TILTON, a citizen of the United States, residing at Pittsburg, in the county of Allegheny and State of Pennsylvania, have invented a certain new and useful Improvement in Washing-Machines; and I do hereby declare the following to be a full, clear, and exact description of the invention, such as will enable others skilled in the art to 5
10 which it appertains to make and use the same, reference being had to the accompanying drawings, and to the letters of reference marked thereon, which form a part of this specification, and in which—

15 Figure 1 is a perspective view of my improvement in washing-machines, representing a portion of the wash-boiler broken away for the purpose of showing the interior arrangement of the cylinder and steam-generator 20 chambers in said boiler. Fig. 2 is a vertical section of the same, and Fig. 3 is a vertical and transverse section of the same.

Similar letters of reference indicate corresponding parts in all the figures.

25 My invention contemplates certain improvements in that class of wash-boilers in which the clothes are washed by placing them in an open cylinder that is hung in the frame of the boiler (immersed in the water) and rotated by 30 a jet of steam and boiling water which is projected upon a series of buckets arranged circumferentially around the cylinder; and it consists in the improved construction and combination of parts, as hereinafter described, and 35 particularly pointed out in the claim.

In the drawings, A is an ordinary wash-boiler, in which, on bearings B B, is pivoted a shaft, C, carrying cylinder D, constructed of closed ends E E and wire-netting F. At 40 the center and around the periphery of the cylinder D is arranged a series of inclined buckets, G.

In the bottom of the boiler is placed, detachably, an open-bottomed box or steam-generating chamber, which is divided by a transverse partition or diaphragm, i, into two compartments, I and J, each compartment being provided with an inward-opening door or valve, denoted by K and L respectively. Midway

on this box is an upward-projecting spout, H, 50 which opens up into a curved open-bottomed conductor, H', that is fastened detachably upon the wall of the boiler by a hooked bracket, h, by means of which the distance of the conductor from the buckets G may be varied at 55 will to regulate the force of the jet of steam and water which is projected up through the spout H.

From the foregoing description, taken in connection with the drawings, the operation 60 of this apparatus will readily be understood. The clothes to be washed are placed inside of the cylinder through a door, m, which is then properly secured, and the cylinder is placed in its bearings B B in the boiler, in the bottom 65 of which the chamber I J has first been placed properly in position. The conductor H' is then, by its bracket h, fitted over the spout H and around the buckets G, when the lid is placed on the boiler, and this, with the suds and water, 70 is placed over the fire. The steam and boiling water in the chambers I J (which are constantly fed through their valves K L) are projected up through the spout H and adjustable open-bottomed conductor H' into the buckets 75 G, thus rotating the cylinder, which, with the clothes, is immersed in the boiling water and suds. By raising or lowering the conductor in respect of the buckets G the jet of steam and water may be regulated to propel the cylinder 80 fast or slow, as desired, according to the condition of the clothes to be washed.

Having thus described my invention, I claim and desire to secure by Letters Patent of the United States—

85 The combination of the boiler A, detachable steam-generating chambers I J, having valves K L and spout H, adjustable conductor H', open on its under side, and open cylinder D, having shaft C and buckets G fitting into the 90 open-bottomed conductor, as set forth.

In testimony whereof I affix my signature in presence of two witnesses.

OLE TILTON.

Witnesses:

HENRY B. TALBOT,
E. W. CALKINS.
